UNITED STATES PATENT OFFICE.

PHIL SHERIDAN, OF BERKELEY, CALIFORNIA.

PILE AND LIKE CLAMP.

No. 818,794.

Specification of Letters Patent.

Patented April 24, 1906.

Application filed June 19, 1905. Serial No. 265,925.

To all whom it may concern:

Be it known that I, PHIL SHERIDAN, a citizen of the United States, residing at Berkeley, in the county of Alameda and State of California, have invented new and useful Improvements in Pile and Like Clamps, of which the following is a specification.

My invention relates to a device for clamping or holding piles and like structures in position while commencing to drive them.

It consists in clamps adapted to inclose the lower end of the cylinder or pile to be driven and means for temporarily locking the clamps until the pile is started.

15 In the accompanying drawings, Figure 1 is a plan view. Fig. 2 is an elevation. Fig. 3 is an enlarged view of the jaw of the clamp.

It is the object of my invention to provide a means for steadyng and guiding piles, and 20 particularly hollow piles which are built up of staves and of larger diameter, running from three to five feet. It is difficult to steady and guide such structures and hold them in proper position so that they will be correctly placed and started.

25 As shown in the drawings, A represents a portion of the frame of the pile-driver.

2 is a cylindrical hollow pile which it is desirable to drive and to guide and to hold into 30 position while driving.

3 represents clamping-timbers, which may be preferably about sixteen inches wide and six inches thick. These timbers are of considerable length and at the rear end are secured to the pile-driver frame by sufficiently large bolts, as at 4, and these bolts form pivots about which the clamps are movable. The opposite ends of the clamps have their inner faces cut to a curvature, as at 5, which 35 is approximately of the same radius as the periphery of the pile to be driven. This curved inner surface is protected by narrow metal plates 6, which are fitted to the surface and extend outward from the curve and are 40 securely bolted through the clamp-timber 3. That portion of the metal strips which extends over the curved inner face is rounded or convexed, as shown at 7, so that there will be no angles to catch upon the hoops 8, by 45 which the staves of the pile are banded. These hoops are made in segments and bolted together, and the flanges of the hoops are so placed when the pile is in position for driving that they will not come in line with the position of the clamps. When the pile is placed,

the clamps are closed, so that the pile is clasped within the inner curve of the clamp 5.

In order to lock the clamps and prevent their being spread, I have shown latches, as at 9. These latches may be made of timber 60 having notches formed in them, as at 10, and these notches are adapted to engage the outer sides of the clamping-timbers 3 after the clamps have been swung into contact with the pile. These pawl-timbers are pivoted to 65 a fixed part of the pile-driver or framework, as shown at 11, and may be turned or tilted back about their pivot-points so as to be out of the way while the pile is being swung into place. When the pile has approximately 70 reached the position where it is desired to drive it, the clamping-timbers 3 are closed in upon each side of the pile, and the pawls 9 are then dropped, so that the notches 10 will engage the outer side of the clamping-timbers, 75 and thus hold them in place.

The pile is driven in the usual manner by blows or pressure and is retained in the desired line in which it is to be sunk by these clamps, which offer no hindrance to its being 80 freely driven.

Having thus described my invention, what I claim, and desire to secure by Letters Patent, is—

1. A device for guiding and steadyng piles 85 while being driven, said device comprising a framework, clamps pivoted to the framework and closable horizontally to clasp the lower part of the pile, and members on the framework movable into contact with the closed 90 clamps and holding said clamps against outward movement.

2. A device for guiding piles to be driven, said device comprising timbers pivoted to open and close horizontally with relation to 95 the pile, said timbers having their inner guide-faces of contact made concaved, and pawls or stops engaging the clamps to hold them in position.

3. A device for guiding piles to be driven, 100 said device comprising pivoted horizontally movable clamping-timbers, having the inner guide-surfaces made concave, metal strips bolted to the timbers forming shoes for the concaved surfaces, and pawls or stops to retain the timbers in position.

4. In a device for guiding piles to be driven, pivoted horizontally opening and closing clamping-timbers having concaved faces adapted to fit about the sides of the pile, 110

metal strips forming shoes for the concavities of the clamps, said strips having their contact-faces made convexed in vertical section, and pivoted pawls or stops having notches 5 adapted to engage the outer edges of the clamps between the timbers to hold them in position.

In testimony whereof I have hereunto set my hand in presence of two subscribing witnesses.

PHIL SHERIDAN.
